UNITED STATES PATENT OFFICE.

NEIL MCKAY, OF PATERSON, NEW JERSEY, ASSIGNOR TO CHARLES H. OTIS,
OF BROOKLYN, NEW YORK.

SNOW-PLOW ATTACHMENT.

SPECIFICATION forming part of Letters Patent No. 505,950, dated October 3, 1893.

Application filed September 21, 1892. Serial No. 446,376. (No model.)

To all whom it may concern:

Be it known that I, NEIL MCKAY, a citizen of the United States, residing at Paterson, Passaic county, New Jersey, have invented 5 a new and useful Improvement in Snow-Plow Attachments, of which the following is a full, clear, and exact description, reference being had to the accompanying drawings, in which—

Figure 1 is a side elevation, partially in section and with the wheels on the near side removed to clearly show other parts, these parts being shown in operative position. Fig. 2 is a similar view showing my plow-attachment and ice-cutter raised out of contact, or in an 15 inoperative position. Fig. 3 is a plan view of the same, parts being broken away. Fig. 3^a is a detail top view of the cam mechanism. Figs. 3^b and 3^c are detail views of the butt-joint. Fig. 4 is a rear view of the flanger. 20 Fig. 5 is an enlarged side view, partly in section (and with the near wheel removed) of the device for cutting ice from the rails. Fig. 6 is a detail front view of one side of the ice cutting mechanism with the wheel and track. 25 Fig. 7 is a side view in detail of the cam-mechanism. Fig. 8 is another side view of the same, showing the latch *e*⁴ out of engagement. Fig. 9 is a detail horizontal section through a truck-wheel and posts showing the relation 30 of the scraping blade and cutter to the rail and wheel. Fig. 10 is a detail vertical section through a truck-axle showing the means of securing the cutter section *D* to the axle.

My invention relates to new and useful improvements in snow-plow attachments, and consists in the novel arrangement and combination of parts hereinafter described and specifically pointed out in the claims.

The main object of this invention is to provide a new and useful means for removing ice from the inner sides of rails, behind a suitable snow-plow, so that the flanges of the truck-wheels shall not meet with or ride on any ice that would otherwise adhere to the 40 rails in spite of the action of an operative snow-plow in front. But the invention is also applicable without a snow-plow.

Another object is to train the tops of rails of any adhering ice.

50 Another object of my invention is to provide a "flanger" for removing any snow from

between the rails which might have remained in place after the regular snow-plow has done its work for automatically raising this flanger out of contact with the snow or ice when an 55 obstruction is encountered on the rail by the ice cutter in front, thus avoiding danger by breakage.

My improved attachments may be mounted on an ordinary car and used in connection with any suitable snow-plow, the ice-cutter being placed preferably in front of the front wheels of the truck and the flanger preferably placed between the trucks and in the rear of the ice-cutter.

In the accompanying drawings *A* designates the flooring of a car to which my improvements are applied and which are supported in any suitable manner, as by trucks *a* in general use.

The ice-cutter whose purpose is to slice off any snow or ice that may adhere to the inner edges of the rails, consists mainly of an ice-cutter-bar *B*, which is provided at its lower end with an upright cutter *b'* for the purpose 75 of cutting the ice from the inner face of the rail in front of the flange of the wheel. The cutter-bar *B*, for the purpose of also scraping snow and ice from the top of the rail, can also be provided with an outwardly projecting horizontal scraper *b*² which by preference is removably attached to the cutter bar *B*, so that it may be removed and replaced by new pieces when worn out. It may here be observed that the upper portion of the scraper 80 *b*² is curved outward as in Figs. 5 and 9, so as to throw the ice, &c., scraped from the rails, up and out to the outer side of the track.

The cutter bar *B*, carrying the upright cutter *b'* and the scraper *b*² is pivoted at *b* to the 90 front section *C* of the ice-cutter frame which is pivotally supported by the axle *c* of the front wheels of the truck in any suitable manner.

The rear section *D* of the ice-cutter-frame 95 is pivotally suspended (see Fig. 10) from the rear truck-axle *d*. The front and rear ice-cutter frame sections *C* and *D* are pivoted together as at *c'* so as to form a butt-joint as shown in Figs 3^b and 3^c. I preferably make 100 the section *D* vertically adjustable on the axle *d* (see Fig. 10) by means of the screw-

bolts d' formed on the yoke d^2 that embraces the axle d or by any other suitable means. The purpose of this adjustment is, that when the socket c^2 of the front section C wears 5 on the front axle c and thereby lowers the cutter-bar B with its cutters, it will not be necessary to remove the said socket c^2 , which would cause much delay and trouble, but the end D of the cutter frame section can 10 be lowered sufficiently to raise the cutter-bar B the desired height, and thus compensate for the wear on the supporting parts. The upper end of the cutter-bar B is connected by a pivot e to a spring-pressed rod b^3 which operates within the casing b^4 rigidly attached to 15 and carried on the forward cutter frame section C. It will be observed that by this construction the cutter-bar B is normally held in a substantially vertical position, the coil-spring b^5 exerting a pressure against a disk carried 20 on the rear end of the rod b^3 .

As far as described the parts are duplicated 25 on the machine, so that there is a cutter-bar B above the inner face of each rail, both adapted to shave the ice from the inner sides of 30 said rails. The two cutter-bars B may be braced and protected from lateral displacement by a bar b^6 which extends between them from one to the other. Connected to this 35 brace b^6 may be attached a rod or chain (not shown) which extends up into the cab or car and which may be controlled by suitable mechanism to raise and lower it, thereby raising or lowering both cutter bars B out and 40 into contact or out and into operative position.

The pivot or bolt e is connected by a rod e' with an arm e^2 loosely carried on a shaft e^3 whose bearings are in the frame of the truck. To this arm e^2 is also attached a latch e^4 which 45 when the cutter-bar B is in a normal position will engage a cam f rigidly attached to the shaft e^3 , as clearly shown in Fig. 5. Extending from this shaft e^3 and also rigidly attached thereto is the crank-arm e^6 which crank-arm is in its turn connected to a link e^7 . This link e^7 is joined by a connecting rod e^5 to a lever E, so that the pivotal point between e^7 and e^5 will be in the center of the truck when the parts are in operative position, thus allowing 50 the truck to assume any angle in turning curves, &c., without detriment to the mechanism employed. The shaft e^3 is or may be loosely hung in a downwardly extending bracket F projecting from the car-platform. The bracket F is also provided with a stationary cam f' , which cam may also, if desired, form one of the bearings for the shaft 55 e^3 . This cam f' I term the riding cam. Its object is to raise the latch e^4 out of engagement with the cam f at a certain predetermined point, and allow the loosely carried arm e^2 to travel a considerable distance in excess of that traveled by the cam f , for purposes which will be hereinafter described.

G is the flanger. It is preferably made of sheet metal and in general construction is somewhat similar to the auxiliary plows now

used; that is, it is made substantially V-shaped, and is provided with concave faces. This flanger is located between the trucks of 70 the car. At the point of this flanger is a metallic cutting edge g , Fig. 1, made considerably heavier than the body of the sheet metal flanger. On the nose of the flanger are located heavy cutting plates g' with suitable 75 means for removing the same, so that they may be replaced by new pieces when worn out and which also provide reinforcing means for the nose, as shown in Fig. 4. The rear half of the flanger is provided with reinforcing plates g^2 to better support the metal from the heavy pressure brought to bear on the flanger at this place, and in addition to these reinforcing plates g^2 I deem it desirable to secure removable wearing plates g^5 where the 85 flanger comes in contact with the rails.

Between the wearing plates g^5 and the cutting plate g' is secured a removable plate g^4 which is made preferably of cast iron. This plate is located on the flanger, so that one end 90 thereof will be near the rail when the flanger is down in an operative position, and each one extends toward the center of the track, when it reaches contact with the nose cutting plate g' . The object of this cast iron plate 95 g^4 is to clean the snow from between the tracks, but should an obstruction too hard to cut through occur, such as an inside rail or the like, the plate g^4 would be broken off without injury to the other parts, when a new 100 one could be readily attached with little expense and delay. It will be observed that the rear upper edges g^3 of the flanger are somewhat twisted or curved from the center of the concave, whereby the snow when carried along the concave faces will be forced out and up from the side of the flanger and 105 roadbed.

Near the rear end of the flanger G and extending from each side thereof is secured the 110 brace-bar H. At the center of this bar H is pivoted the link h which, it will be observed, allows the double movement of the flanger, for purposes hereinafter described. This link 115 h is in its turn pivotally secured to the lever I, which at I' is pivoted to the car.

On each side of the lever I and rigidly attached to its pivot I' are crank-arms I² I³ which connect with pieces of chain to the bar H. At the upper edge of the forward portion of the flanger is secured a link i' which is supported at the other end to the bottom of the car or at any other desirable point. It will be seen that by this particular arrangement, I am enabled to exert a pressure on the 120 flanger through the lever I and at the same time allow one side of the flanger to rise slightly when an obstruction too great to cut through is reached, without the necessity of the opposite side rising with it. This construction is 125 of great advantage in rounding curves where the rails at each side of the track are on different horizontal planes, sometimes there being a difference of six inches, and it will be

seen that my flanger instead of rising to a level of the highest rail, has an equal pressure exerted on both rails.

J designates a cylinder provided with a piston and piston-rod j and steam chest which is entered by a valve-rod j' , the outer end of which valve-rod is secured to lever K by a link k and bell-crank lever k' or any other connection. The lever E is also suitably connected with the valve-rod j' , as shown at j^2 .

The piston may be operated by any means, such as steam, compressed air, &c., which may be conveyed from any suitable source.

The operation of my improved attachments I will now proceed to describe as follows: The train is supposed to be moving in the direction of the arrow, with the attachments in operative position, as clearly shown in Fig. 1. When the ice-cutter b' strikes an obstruction on the rail or at the side thereof, too hard to cut through, such as a frog or the like, the lower end of the cutter-bar will be thrown back, so as to ride over the obstruction, thereby elevating the forward end of the section C, since it is pivotally carried on the axle c . The other end of section C is lowered and the butt-joint between C and D opened as in Figs. 2 and 3^c. At the same time the upper end of the cutter-bar B with the spring-pressed rod b^3 and link e' attached thereto is moved forward, thus communicating motion in the same direction to the arm e^2 with its latch e^4 (see Fig. 8). By this action the cam f , which is rigidly secured to the shaft e^3 and has crank-arms e^6 rigidly attached thereto, is turned, and moves by the connections e^7 and e^5 the lever E, which serves to throw the valve of the cylinder J. This action of the valve in steam chest causes the piston to be forced out and thus to raise the flanger G (Fig. 2) (by the lever I) off the track, out of contact with the snow, and consequently out of all danger of the obstruction which originally lifted the ice-cutter b' . As heretofore described, the latch e^4 nominally engages the operating cam f until it reaches the stationary riding cam f' , when it slides or rides thereon out of engagement with the cam f , and continues its movement forward as far as necessary (Fig. 8), the limit thereof being determined by the obstruction encountered or the backward throw of the ice-cutter b' . When the ice-cutter b' has passed over the obstruction, the spring b^5 (which all this time has been compressed) forces out the rod b^3 , the cutter-bar B, link e and loosely mounted arm e^2 carrying the latch e^4 , resume their normal positions, as shown in Fig. 5, and the upward pressure being relieved from the forward end of the cutter frame section C by the cutting-bar B regaining its normal position, will allow the frame sections to regain their normal positions, as shown in Fig. 1. The arm e^2 being loosely mounted on the shaft e^3 , the movement back to normal position does not affect said shaft e^3 , and consequently does not affect the valve-controlling mechanism; so it will be seen that the flanger G when once

raised, remains raised, until lowered by the operator through the lever K, link k and lever k' , which controls the valve of the cylinder J. When the flanger G is lowered through this means, the cam f on the shaft e^3 is again thrown back in engagement with the latch e^4 by the operation of the lever E and link e^5 connected to the crank-arms e^6 . Said flanger G is then ready to operate as before or to be raised to avoid the next obstruction. It will further be seen that by this construction the flanger is only automatically raised, and that the ice-cutters after having passed the obstruction can continue to operate without the necessity of lowering the flanger. I am also enabled by this construction to raise or lower the flanger entirely independent of the ice-cutters.

It is obvious that I may modify my constructions considerably in detail without departing from the spirit of my invention.

When the apparatus operates, the cutters b' pare the ice from the inner sides of the rails, the cutters b^2 pare it from the tops of the rails, and the flanger G throws out any snow left between the rails after the front truck has passed. The spring b^5 gives a yielding pressure to the cutters, but permits them and the flanger to ride safely over any rigid obstruction.

Having described my invention, what I claim is—

1. The combination of the cutter bar B with the jointed and pivoted sections C D, spring b^5 , cutter or cutters on said bar B and with a truck carrying said sections C D and holding said spring, as specified.
2. The combination of the spring-pressed cutter-bar B, cutter b' , and adjustable and movable frame sections C and D pivotally connected to said cutter-bar B, substantially as described.
3. The combination of crank shaft I', lever I, flanger G and link h connecting said flanger G and lever I, substantially as described.
4. A snow-plow or flanger consisting of concaved sides, reinforcing plates g^2 , plates g^4 , and wearing plates g^5 mounted thereon, the outward ends of said sides being curved or twisted upwardly, substantially as described.
5. The combination of knuckle-jointed sections C D, cutter b' pivotally mounted on one of said sections, said sections C and D being adapted to lock when the cutter is in operative position and adapted to be opened when said cutter b' is being forced out of operative position, substantially as described.
6. The combination of ice-cutter b' , flanger G, and an engine interposed substantially as described for automatically raising said flanger when the ice-cutter comes in contact with an obstruction and thereby sets the engine into action, all as specified.
7. The combination of ice-cutter b' , flanger G, and an engine interposed substantially as described for automatically raising said flanger when the ice cutter b' comes in con-

tact with an obstruction and mechanism substantially as described for reversing said engine and lowering said flanger G independent of said ice-cutter b', substantially as described.

8. The combination of the spring-pressed ice-cutter b', flanger G and an engine interposed substantially as described for automatically raising said flanger G when the ice-cutter b' encounters an obstruction, and with

mechanism substantially as described whereby said spring-pressed ice-cutter automatically regains operative position independent of said flanger G, after the obstruction is passed, substantially as described.

NEIL MCKAY.
